HYDROMASSAGE DEVICE

Charles Aimé Fortin, Montreal, Quebec, Canada, assignor to Paul Pouliot, Cote des Neiges, Quebec, Canada

Application September 8, 1953, Serial No. 378,916

6 Claims. (Cl. 128—66)

The present invention pertains to a novel hydromassage device designed for use on the face although applicable to other parts of the body.

The principal object of the invention is to provide a device for strengthening the tissues, toning up the muscles and thereby removing or reducing wrinkles especially on the face. Another object is to provide a pulsating intermittent stream of cold water against the skin, whereby to produce a vibratory massage effect on the skin, resulting in the described effect.

In the accomplishment of these objects, the device includes a tube having at one end a mask applicable to the face or other part of the body. In the body is mounted a rotor housing with a rotor therein. A cold water pipe extends into the housing. The water is discharged from the rotor into the mask and is exhausted at the opposite end of the body.

The pulsating effect is obtained by unbalancing or varying the rate of flow of water. In one or more embodiments of the invention, one of the rotor blades is heavier than the others to produce the pulsating flow. In another embodiment a valve device is actuated by the rotor for the same purpose. In still another form, the rotor is spirally fluted, and one of the flutes or passages is partially filled to unbalance the rotor.

The invention is fully disclosed by way of example in the following description and in the accompanying drawings in which:

Figure 1 is a side elevation of the device;
 Figure 2 is a longitudinal section;
 Figure 3 is a perspective view of the rotor;
 Figure 4 is a section on the line 4—4 of Figure 2;
 Figure 5 is a longitudinal section of a modification;
 Figure 6 is another longitudinal section of Figure 5;
 Figure 7 is a section on the line 7—7 of Figure 6;
 Figure 8 is a longitudinal section of a further modification;

Figure 9 is an elevation of the rotor thereof;
 Figure 10 is a section on the line 10—10 of Figure 9;
 Figure 11 is a section on the line 11—11 of Figure 8; and

Figure 12 is a longitudinal section of still another modification.

Reference to these views will now be made by use of like characters which are employed to designate corresponding parts throughout.

In Figure 1 is shown a cylindrical body 1 to which is applied a funnel-like member or mask 2 made of rubber or plastic material. A cold water inlet tube 3 connects with the body 1 near the mask 2, and the body itself is the water outlet as will presently be shown.

Within the body is a cylindrical housing 4 at the inlet 3 and connected to the latter by a nozzle 5. In the housing is mounted a rotor 6 on a transverse shaft 7. The rotor is comprised of radial blades 8, one of which is of greater thickness and weight as indicated at 9.

The nozzle 5 is restricted at 10 toward the rotor to throw a jet against the blades. The blade 9, although of such size as to obstruct the nozzle, is formed with an outer pocket 11 to pick up water and therefore avoid complete interruption of the flow. The forward half of the housing 4 is apertured at 12 to permit flow of water into the mask 2.

In use, the mask is applied firmly to part of the face and moved horizontally while the water is flowing. The rotor is unbalanced by the heavier blade 9, thereby causing a pulsating or varying the rate of flow of water. The

2

result is a vibratory effect or hydro-massage, which has been found beneficial in toning the muscles and tissues of the face and removing wrinkles. The water exhausts at the opposite end of the body.

Similar results are obtained by the modifications that will now be described. In Figures 5-7 a cylindrical shell 15 is mounted in the body 16 coaxial with the body and the mask 17. A rotor housing 18 in the shell connects with an inlet pipe 19 through a nozzle 20. A blade rotor 21 is mounted in the housing 18 on a transverse shaft 22 as previously described.

The housing 18, however, is semi-spherical and communicates forwardly with the shell 15. At the forward end of the shell is a perforated outlet cap 23. Inside the cap is a slidable block 24 connected eccentrically to the rotor 21 by a link 25. The block has longitudinal passages 26 for the flow of water. The oscillation of the block by this means produces pulsation of the stream for the purpose described above.

The modification shown in Figures 8-11 embodies a body 30, mask 31, shell 32, inlet pipe 33, and perforated cap 34, as in Figure 5. The bladed rotor 35, however, is mounted on a longitudinal shaft 36 supported by a disk 37 fitted in the shell. The shell forms the rotor housing, and receives water from the inlet 33 through a nozzle 38. A heavier rotor blade 39 is provided to introduce the desired pulsations.

The embodiment shown in Figure 12 also has a body 40, mask 41, shell 42, and perforated cap 43, as in Figures 5 and 8. The rotor 44 turns on a longitudinal axis in the shell and is a spirally fluted member having outer spiral grooves 45. One of the grooves is partially filled at 46 for the unbalanced and pulsating effect previously described and common to all embodiments of the invention.

Although specific embodiments of the invention have been illustrated and described, it will be understood that various alterations in the details of construction may be made without departing from the scope of the invention, as indicated by the appended claims.

What I claim is:

1. A hydromassage device comprising a tubular body, a mask at one end thereof, a rotor housing in said body, and having communication with both ends of said body as fluid outlets, an inlet pipe extending into said housing, a rotor in said housing, and means movable with the rotor for varying the rate of flow to said mask to introduce pulsation of the flowing fluid.

2. A hydromassage device comprising a tubular body, a mask at one end thereof, a rotor housing in said body and having communication with both ends of said body as fluid outlets, an inlet pipe extending into said housing, a rotor in said housing, said rotor having blades, one of said blades being heavier than the other, to introduce pulsation of the flowing fluid.

3. A hydromassage device comprising a tubular body, a mask at one end thereof, a rotor housing in said body, and having communication with both ends of said body as fluid outlets, an inlet pipe extending into said housing, a rotor in said housing, said rotor having blades, one of said blades being heavier than the other, to introduce pulsation of the flowing fluid, the last named blade having an outer pocket adapted to pass said inlet pipe, whereby to prevent total interruption of the flow.

4. A hydromassage device comprising a tubular body, a mask at one end thereof, a shell coaxial in said body and communicating with said mask and with the other end of said body, a perforated cap on the end of said shell at said mask, a bladed rotor in said shell, an inlet pipe extending into said shell at said rotor, a block with fluid passages slidably mounted in said shell at said cap, and a link connecting said block eccentrically to said rotor.

5. A hydromassage device comprising a tubular body, a mask at one end thereof, a shell coaxial in said body and communicating with said mask and with the other end of said body, a perforated cap on the end of said shell at said mask, a shaft supported axially in said shell, a bladed rotor on said shaft, an inlet pipe extending into said shell at said rotor, a block with fluid pas-
